UNITED STATES PATENT OFFICE.

GEORGE S. LEWIS, OF SPRINGFIELD, MASSACHUSETTS, ASSIGNEE TO J. STEVENS ARMS & TOOL COMPANY, OF CHICOPEE FALLS, MASSACHUSETTS, A CORPORATION OF MASSACHUSETTS.

FIREARM.

1,086,378.

Specification of Letters Patent. Patented Feb. 10, 1914.

Application filed August 18, 1913. Serial No. 725,393.

To all whom it may concern:

Be it known that I, GEORGE S. LEWIS, a citizen of the United States, residing in Springfield, Hampden county, State of Massachusetts, have invented certain new and useful Improvements in Firearms, of which the following is a specification, reference being had to the accompanying drawings, which form a part hereof.

10 This invention is particularly concerned with the lock mechanism of sporting guns. It is shown and described herein as embodied in a double-barreled, breech-loading shot gun to which some of the improvements 15 are especially applicable, but other features of improvements, as will be understood, are applicable also to other types of firearms.

10 The immediate object of the invention is to simplify construction and reduce the number of parts, thereby lessening the cost of manufacture and liability to derangement and breakage, but safety in use is also a consideration.

15 The hammer is of the rebounding type and some of the features of the invention relate thereto. The triggers are arranged in tandem but in such a manner that the leverage and consequently the pull of the two triggers is the same.

20 Other features of improvement will be referred to hereinafter.

25 In the accompanying drawings in which the invention is illustrated—Figure 1 is a view in side elevation of a gun which embodies the invention. Fig. 2 is a view on a larger scale, partly in elevation and partly in longitudinal section, of so much of the gun shown in Fig. 1 as is necessary for the purposes of explanation of the invention, the 30 parts being shown in the positions which they occupy when the left hand hammer is down and the right hand hammer is cocked, the latter being shown by dotted lines. Fig. 3 is a view similar to Fig. 2, with the parts in the 35 positions which they occupy when the right hand trigger has been pulled, the rebound position of the tumbler being indicated by dotted lines. Fig. 4 is a top view partly broken out to show the hammer springs, the top lever actuating rod being shown in dotted lines. Fig. 5 is a view in section on the plane indicated by the broken line 5—5 of Fig. 2. Fig. 6 is a view in section on the plane indicated by the broken line 6—6 of Fig. 2. Fig. 7 is a view in perspective of

the right hand tumbler and bushing. Fig. 8 is a similar view of the left hand tumbler, but showing the opposite face.

The stock *a*, barrels *b*, and the grip-piece or fore-end *c* may be constructed and arranged as usual and the barrels may be hung upon the frame *d* in the usual manner, being retained in position by the usual top lever *e*. The frame, trigger plate and tang, which are usually made in separate pieces, in this 60 construction are made in one integral piece *d* which together may be called the frame. In this frame are mounted all of the movable parts.

Each hammer *f*, having as usual a square hole, is held by a screw *f'* upon a squared end of a corresponding tumbler *g*. The latter has at its inner end a stud *g'* by which it is mounted in a suitable bearing in an integral rib *d'* of the frame *d*, the rib *d'* furnishing a bearing for both tumblers *g*. Each tumbler, near its outer end, has a bearing in a bushing *h* which is seated in the side of the frame and has a shoulder *h'*. The two bushings are held in place respectively by 70 the head *i'* of a rod *i*, on one side, and, on the other side, by the head of a screw *i'* which is tapped into the rod *i* which passes through the frame. Each tumbler is formed, 75 near its inner end, with a main spring lug *g''* which has a socket *g'''* to receive the end of the main spring plunger, and, diametrically opposite the main spring lug *g''*, with a sear lug *g'''*.

80 The main spring plunger *k*, having a head *k'*, with a conical point *k''* to coöperate with the main spring lug *g''*, and a rebound shoulder *k'''*, is guided at its rear end in the sleeve *k''*, suitably supported at the rear end of the frame, and receives the coiled 85 main spring *k''*. The shoulder *k'''* of the head of the main spring plunger coöperates with the rod *i* above mentioned for the purpose of limiting the forward movement of the main spring plunger and of relieving 90 the hammer of the pressure of the spring *k''* before the hammer reaches the limit of its forward movement, so that the effective movement of the hammer upon the firing pin *b'* is accomplished by the momentum of 95 the hammer alone.

100 The right hand trigger *m* and the left hand trigger *n*, are separately pivoted, as at *m'* and *n'* respectively, in the frame and the forward arm *m''* of the trigger *m* bears 105

the same relation to the lower arm m^3 that the forward arm n^2 of the trigger n bears to the lower arm n^3 , by reason of the pivoting of the trigger n at a point above and to the rear of the pivot m' of the trigger, so that the two triggers have the same leverage and the same pull. The two triggers are so shaped that the arms m^3 and n^3 are in line, while the arms m^2 and n^2 are offset so that they may engage properly with the respective sear lugs. The two triggers are acted upon by a single, common trigger spring o which has a middle coil, hung upon the pivot n' , while its ends engage respectively a pin m^4 on the trigger m and a pin n^4 on the trigger n . Not only is the construction simplified and the number of parts reduced by arranging one spring to act upon both triggers, but, as will be observed, this is a feature of safety, for as pressure is put upon one trigger, by the finger, to release it, the pressure of the spring against the other trigger, to hold it in place is increased, so that there is less liability of an unintentional movement of the second trigger when either one is pulled.

When either hammer is released, it swings forward, under the influence of the main spring k^c , until the shoulder k^3 strikes against the rod i and thereafter the movement of the hammer is continued by its momentum alone. The sear lug g^4 on each tumbler g is formed, forward of the forward notch, with a cam projection g^5 which, when the hammer is in its extreme forward position, rests against the extremity of the arm m^2 or n^2 of the spring-pressed trigger. The action of the trigger arm under the influence of the spring against the cam surface g^5 is to cause the hammer to swing back from the firing pin or to rebound, so that the hammer is left free of the firing pin when it comes to rest. By this construction the employment of a separate rebounding spring or the construction of the main spring plunger to coat on the tumbler is avoided and a simple and efficient means for effecting the rebounding of the hammer is provided.

For further simplification of the gun, the spring e' for the top lever e is arranged to act directly upon the top lever through a plunger rod e^2 which is upturned at its forward end, as at e^3 , to pass through a slot (not shown) in the top of the frame and enter a recess, indicated at e^4 , in the underside of the top lever e . The rod e^2 is provided with a shoulder e^5 against which the forward end of the spring e' may bear and its rear end is guided in a hollow screw e^6 which is threaded in the rear end of the frame and bears against the rear end of the spring e' .

The vertical frame d , chambered at d^b to

receive, between the forward solid portion d^a and the rear solid portion d^c the various moving parts referred to above, is set into the forward end of the stock a , as clearly shown in the drawings, and is secured in place therein by a long screw d^4 which is passed through the stock from the rear and is tapped into the rear end d^3 of the frame. With this construction no other screws are required to hold the stock and frame together.

It will now be understood that some of the features of the invention referred to are capable of application to single barreled firearms and that the several features of the invention are not necessarily employed together in one structure but may be employed independently. It will also be evident that the invention is not restricted to the details of construction shown and described herein.

I claim as my invention:—

1. In a firearm, the combination of a frame, a hammer tumbler mounted therein, a flanged bushing mounted in the frame and supporting one end of the tumbler and a screw rod extended across the frame and having a head to engage the flange of the bushing and retain the same in position.

2. In a double-barreled firearm, the combination of a frame, hammer tumblers mounted therein and having each a sear lug and triggers mounted in the frame and coöperating with the sear lugs, the triggers being pivoted at different points in the frame one in advance of the other whereby both triggers may have the same leverage.

3. In a firearm, the combination of a frame, triggers pivoted separately in the frame one in advance of the other and a single, common trigger spring coöperating with both triggers.

4. In a firearm, the combination of a frame, hammer tumblers mounted in the frame and having each a sear lug, and triggers mounted in the frame in tandem, the pivot of one of the triggers being above and behind the pivot of the other whereby the triggers have the same leverage.

5. In a firearm, the combination of a frame, triggers mounted therein in tandem on independent pivots and a single, common trigger spring having a central coil about a pivot between the pivots of the triggers and having its ends coöperating with the triggers respectively.

This specification signed and witnessed this 11th day of August A. D., 1913.

GEORGE S. LEWIS.
